UNITED STATES PATENT OFFICE.

SIMEON K. MARKMAN, OF OAK PARK, ILLINOIS, ASSIGNOR TO ROBERT M. LACKEY,
OF COHOES, NEW YORK.

HANDLE BAG OR ENVELOPE.

Application filed March 14, 1927. Serial No. 175,072.

The invention relates to handle bags or envelopes, and particularly to the type of paper bags, envelopes, folders or other containers for holding and carrying relatively 5 light-weight goods, wares and merchandise of various descriptions.

One of the objects of the invention is to use any ordinary flap bag or envelope and secure a pair of handles to the bag or envelope, one of the handles being secured to the front and the other to the back, but in such a manner that the flap of the bag or envelope will be turned down and close the opening of the bag or envelope against the 10 admission of rain or foreign matter, and prevent the goods from dropping out of the bag or envelope, and all without deforming the bag or envelope, or the flap thereof, or cutting into them, the handles being brought 15 together and locked.

Bags, envelopes and other containers embodying the invention are frequently used for holding and carrying sheer silk materials, such as hosiery, lingerie, gloves and 20 other goods, which may be damaged if they come in contact with the slightest obstruction or interference whatever. It is an additional object of the invention to secure each of the handles of the bag or envelope 25 in such a manner that they do not interfere in the slightest with the insertion of the merchandise, such as the sheer silk materials referred to, into the bag or envelope, or its withdrawal therefrom, the inside of the bag 30 or envelope and also the projecting flap thereof being free from all cutouts, slits, slots, attachments, or any other obstruction or interference.

Another object of the invention is to secure the handles of the bag or envelope by the use of adhesive, causing the handle to be secured in certain places on the front and back of the bag or envelope, causing accurate registering of the apertures in the 45 handle, together with the proper functioning of the handle lock.

It is a further object of the invention to form the handles of the bag or envelope in such a manner that positive locking of the 50 bag or envelope is secured, and the handles themselves are automatically maintained in a locked relationship.

An additional object of the invention is to provide handles for the bag or envelope 55 which may readily be grasped and held to

initially open the bag or envelope, to permit the ready insertion of the merchandise into the bag while it is being held by the handle secured to the back of the bag or envelope.

It is also an object of the invention to provide an envelope or bag which supplies the maximum amount of storage space within the bag or envelope, without sacrificing the efficient disposition and operation of the flap 60 of the bag or envelope, the handles therefor, and the locking means.

In connection with the shipping of the bags or envelopes containing the invention to dealers, storekeepers and others, and the 70 storage of the same prior to their use by the ultimate consumer, it is a further object of the invention to form the bags or envelopes, and the handles therefor, in such a way that they lie flat, with their flaps up between the 75 handles, the tops of the handles being preferably coincident with each other, thus making up packages without waste of space.

An additional object of the invention is to provide separate carrier handles for any 80 style or shape of bag, envelope, folder, box, package, or other container, which handles have adhesive placed upon them in certain positions, so that they may be directly and suitably affixed by the manufacturer, dealer 85 storekeeper, or others, upon the front and back of the bag, envelope, folder, box, package or other container, so that the merchandise may be held in a locked handled carrier.

A further object of the invention is to 90 cause the front and back of the bag, envelope or other container, when merchandise is contained within the same, to be drawn upwardly and equally within the bag or envelope against the merchandise, since the 95 handles are formed in such a manner, and affixed to the front and back walls of the bag or envelope in such a way that they, together with their finger holes, register with each other and enable the two handles to be 100 locked together in such registry, thus securing a relatively tight and even fit between the bag or envelope and the merchandise, and presenting a neat appearance when being carried.

Frequently, before or after leaving the place of purchase, the customer desires to reinspect and examine the merchandise which has been purchased, and which is enclosed in the bag or envelope, for the 110

purpose of verifying the purchase or for any other reason. The invention permits the ready and quick unlocking of the handles and opening of the bag or envelope for the 5 reinspection of the goods, and upon conclusion thereof, the ready and quick turning in of the flap and the relocking of the handles.

An additional object of the invention is 10 that the carrier handles are so placed on the front and back of the bag or envelope that at the time of opening of the bag or envelope for inspection or delivery of the contents, the entire flap is wholly and entirely free 15 from both handles, and thus enables the full and maximum opening and expansion of the bag or envelope at its mouth for the extraction of the merchandise.

The invention will be explained and more 20 readily understood when read in conjunction with the accompanying drawings illustrating one embodiment of the invention, but it will be understood that various changes and modifications of which the 25 invention is susceptible may be made without departing from the spirit of the appended claims forming a part thereof.

In the drawings:

Figure 1 is an elevational view of the 30 front of the bag or envelope with a front handle attached thereto.

Figure 2 is an elevational view of the back of the bag or envelope, the envelope flap, the handle attached to the back, and the locking 35 flap of the front handle.

Figure 3 is an elevational view showing the inside face of the handle for the front of the bag or envelope.

Figure 4 is an elevational view showing 40 the inside face of the handle for the back of the bag or envelope.

Figure 5 is a cross sectional view on the line 5-5 of Figure 1, looking in the direction of the arrows, showing the front and 45 back handles with the locking flap of the front handle in extended position.

Figure 6 illustrates the unobstructed and uninterrupted appearance of the interior of the bag or envelope and its flap on the line 50 6-6 of Figure 8, looking in the direction of the arrows, the front handle being shown in dash lines.

Figure 7 is a cross-sectional view on the line 7-7 of Figure 6, looking in the direction of the arrows, and illustrates the bag or envelope in open position with the handles attached, and with goods or merchandise in the bag, but with the flap of the bag extended upwardly to further illustrate 60 the unobstructed and uninterrupted surfaces of the interior of the bag.

Figure 8 is an enlarged sectional view on the line 8-8 of Figure 1, looking in the direction of the arrows, and illustrates the 65 bag in closed position, with the flap turned

down between the rear portion of the bag and the rear handle, but with the locking flap of the front handle depending in the finger aperture.

Figure 9 is a view similar to Figure 8 on 70 the line 9-9 of Figure 2, looking in the direction of the arrows, but showing the locking flap of the front handle in dotted lines as it has come through the aperture in the rear handle, and in full lines, about to 75 be placed against the exterior face of the rear handle to lock both handles, and,

Figure 10 is a view of both front and back 80 of the bag, and both handles with the flap of the bag extended upwardly, and particularly showing where the adhesive is placed to secure the handles to the bag.

The bag or envelope which is used in connection with the invention may be of any size, shape, or form, and may have a flap 85 of any size, shape, or form, and may have either a die-cut, or serrated edge. The bag which is shown in the drawings comprises a front body portion 15 and a rear body portion 16. These portions may be secured 90 together in any suitable manner, as by inwardly extended turned down edges 17 and 18, fastened by suitable adhesive, as shown at 19 and 20. The flap portion of the bag or envelope 21 is an integral portion of the front 15, and extends from an imaginary line drawn across the envelope from the terminals of the adhesive sections 19 and 20, which line is marked 22. The flap extends from this portion of the front 15 of the 100 bag or envelope to the outer edge 23 of the bag or envelope. The flap when folded down into place when the bag or envelope is being used is folded and creased along the imaginary line 22. It will be understood that the flap may be folded and creased on any line 105 transverse of the bag, convenient for closing, that is, either on the line 22 or adjacent thereto. As a general proposition, however, it will be found that the flap 21 will fold and turn most easily on a line coincident with, or substantially coincident with, the top line 24 of the adhesive 25, which adhesive is used to attach the handle generally designated 26 to the front portion of the bag or envelope. Since the bags or envelopes are received by dealers, storekeepers, and others in a flat condition, and without a crease or score along the line 22, the top edge 24 of the adhesive 25 provides a 110 convenient guide for folding the flap.

The line 22 and the top 27 of the rear portion 16 of the bag or envelope are substantially opposite each other, as best shown in Figures 7 and 10, and the top 27 may be 125 straight or slightly curved.

The carrier handle 26, which may be of any desired width or length, and which may be of material of suitable character for the particular bag or envelope to which it is to 130

be affixed, is secured to the front portion 15 of the bag or envelope. It is formed with the portion 28, to which the adhesive 25 is applied, and also is formed with the rounded 5 loop or handle portion 29. The adhesive 25 is preferably, though not necessarily, applied to the entire portion 28 of the front handle, as more particularly shown in Figure 3 of the drawings. The looped portion 10 29 of the handle is provided with the finger aperture 30, and the locking flap 31. The finger aperture 30 may be made wide enough so that the user may insert one, two, three, or four fingers as desired.

15 The locking flap 31 is formed by cutting along the angularly disposed lines 32 and 33, respectively, to form the locking flap extensions 34 and 35 respectively. The locking flap 31 may be bent, to perform its function, 20 along the line 36, which may have a definite scoring, or may be defined by the mere act of bending the locking flap. Ordinarily the material used for handles for bags or envelopes of the kind referred to, is strong 25 enough to permit the bending of the material without breaking or tearing. In affixing the front handle to the front portion 15 of the bag or envelope, the handle is preferably pasted in such a manner that the top line 24 30 of the adhesive 25 registers, and is coincident with the bottom 37 of the finger aperture 30.

The carrier handle 38, which is of the same width and character of material as the carrier handle 26, but not necessarily of the same length, is secured to the rear portion 16 of the bag. It is secured by the adhesive 39 which is placed on the bottom portion 40 of the carrier handle. The adhesive 39 extends from the bottom of the lower portion 40 of the handle, a distance which is relatively shorter than the distance which the adhesive 25 extends from the end of the lower portion 28 of the carrier handle 26.

45 It will be understood, however, that there may be a greater extent of the adhesive 39 in a direction toward the bottom of the bag, but the top line 41 of the adhesive 39, should be down far enough on the rear portion 16 50 of the bag to permit the flap 21 to be turned downwardly against the rear body portion, without being interfered with in any way by the carrier handle 38. While the top line 41 of the adhesive should not come up too far on the bottom portion 40 of the carrier handle 38, it is immaterial how far it extends downwardly on the bottom portion 40, or how long the bottom portion 40 is, except that a good connection of the carrier 55 handle 38 with the bag portion 16 should be made. The upper looped portion 42 of the carrier handle 38 is provided with the finger aperture 43, which may be of a suitable dimension for the insertion of one, two, three, 60 or four fingers, as may be desired. The

finger aperture 43 registers with the finger aperture 30 when the front handle 26 and the rear handle 38 are brought together.

In connection with the operation of the invention, the bag or envelope is taken from the pile by the user and at that time is in a flat condition, with the flap 21 extended outwardly between the two handles 26 and 38, the locking flap 31 lying or depending in the finger aperture 30 with the locking flap extensions 34 and 35 lying in the cutout sections at the sides of the finger aperture 30. The user grasps the upper portion 42 of the rear carrier handle 38, inserts his finger or fingers in the finger aperture 43, and inserts the merchandise 44 into the bag between the outer and inner walls thereof 15 and 16, respectively. The user then folds the flap 21 down against the upper outer side of the rear portion 16, creasing the flap on the imaginary line 22. He then brings the carrier handle 38 upwardly and against the inner face of the carrier handle 26, whereupon the finger apertures 30 and 43 of the carrier handles 26 and 38 respectively are brought into registry. The user thereupon presses the locking flap 31 inwardly through the finger aperture 30 away from the cut lines 32 and 33 and continues to push the locking flap 31 through the finger aperture 43. The side extensions 34 and 35 of the locking flap 31 offer resistance however, to the passage of the locking flap 31 through the finger aperture 43, but the resistance offered by the side extensions 34 and 35, is readily overcome as the user continues to push the locking flap 31 through the aperture 43. After the locking flap 31 has passed through the aperture 43, it is brought upwardly, as more particularly shown in Figure 9 of the drawings, and against the outer face 45 of the upper portion 42 of the rear carrier handle 38.

When the goods are to be removed from the bag or envelope for use, or for inspection, the locking flap 31 is removed from its position against the face 45 of the loop handle portion 42 and returned through the finger aperture 43, the locking flap extensions 34 and 35 snapping against the side edges of the handle portion 42 as the locking flap passes through the aperture. The locking flap 31 is also passed through the aperture 30, or it may depend in the aperture 30. The two handles 26 and 38 are then separated from each other and the flap 21 is brought upwardly against the inner face of the top portion 29 of the handle carrier 26 covering the entire top portion 29, the locking flap 31 and the finger aperture 30, thus presenting the smooth, unobstructed inner surfaces of the body portions 15 and 16 and permitting the withdrawal of the goods 44 without the possibility of harm or injury to them. While the goods 44 are being withdrawn by one hand of the user, the other

holds the handle 38. In the ordinary light weight paper bag employing the invention, by holding the handle 38 the bag is usually held open so that the goods may be readily withdrawn.

Having thus explained the invention, what I desire to secure by Letters Patent is:

1. In a handled bag, envelope or other container, the combination of front and rear body portions, a flap integral with and extending from one of said portions each of said body portions and said flap on the inner faces thereof being continuous and free from any opening, obstruction or interference whatsoever to the entry and withdrawal of merchandise, a pair of handles, each of said handles being affixed to the exterior face of its respective body portion, the handle affixed to said body portion having the flap integral therewith being secured with adhesive, the top line of the adhesive being substantially on a line with the bottom of said flap, the handle on the other body portion being secured to said body portion with adhesive, the top line of said last named adhesive being far enough away from the top line of said body portion to permit said flap to be placed between said last mentioned handle and said last mentioned body portion to close the bag against admission of rain or other foreign matter.
2. In a handled bag, envelope or other container, the combination of front and rear body portions, a flap integral with and extending from one of said portions each of said body portions and said flap on the inner faces thereof being continuous and free from any opening, obstruction or interference whatsoever to the entry and withdrawal of merchandise, a pair of handles, each of said handles being affixed to the exterior face of its respective body portion, the handle affixed to said body portion having the flap integral therewith being secured with adhesive, the top line of the adhesive being substantially on a line with the bottom of said flap, the handle on the other body portion being secured to said body portion with adhesive, the top line of said last named adhesive being far enough away from the top line of said body portion to permit said flap to be placed between said last mentioned

handle and said last mentioned body portion to close the bag, said handles being provided with locking means, said means consisting of apertures in each of said handles which register with one another, a locking flap depending in one of said apertures and adapted to pass through the aperture in the other of said handles, said locking flap being provided with side extending portions at the base portion thereof formed from said handle, causing the lower portion of said locking flap to be wider than the greatest width of the finger aperture of the other handle.

3. In a handled bag, envelope or other container for holding and carrying merchandise, a front body portion having a flap integral therewith, a rear body portion, the interior faces of said body portions and said flap being continuous unobstructed and uninterrupted, handles affixed by adhesive to the exterior faces of each of said body portions, the handle affixed to the front body portion being so affixed that the flap may be folded over the upper portion of the other body portion to close said bag, said handle on said rear body portion locking said flap against said rear body portion and said front handle locking said rear handle to itself, said body portions being drawn together and joined at their top portions by the bringing together of said handles.

4. A shopping bag having an open receiving end and a continuous, unobstructed and uninterrupted closure flap therefor, a bale handle for said bag comprising a plurality of rectangular shape paper sections permanently attached to said bag at the opposite sides thereof, the area of attachment on one of said sections being below and adjacent to the free edge of said flap when disposed in closed position, the free ends of said sections having orifices to register each with the other to form a passage through which the fingers of the hand may be inserted, and a tab on one section for extending through said passage and under the upper boundaries thereof to cover the raw edges of said orifices.

In witness whereof, I hereunto subscribe my name this 3rd day of March A. D., 1927.

SIMEON K. MARKMAN.
